(57) **CLAIM**

The ornamental Design for a surface of a tire, as shown and described.

DESCRIPTION

FIG. 1 is a perspective view of a tire showing our new design, it being understood that the pattern repeats uniformly throughout the circumference of the tread;

FIG. 2 is a front elevational view thereof;

FIG. 3 is a right side elevational view thereof; the opposite side elevational view being identical thereto; and,

FIG. 4 is an enlarged fragmentary front elevational view thereof.

In the drawings, the broken lines showing of the grooves, sidewall, inner bead and the peripheral boundary between the tire tread and the sidewall depict portions of the tire and form no part of the claimed design.
